UNITED STATES PATENT OFFICE.

THOMAS E. ARUNDEL, OF OMAHA, NEBRASKA. ASSIGNOR OF THIRTY-SEVEN AND ONE-HALF PER CENT TO GUY D. SHIPHERD AND TWENTY-FIVE PER CENT TO WILLIAM H. METCALFE, BOTH OF OMAHA, NEBRASKA.

RADIO RECEPTION APPARATUS.

Application filed March 12, 1925. Serial No. 14,922.

To all whom it may concern:

Be it known that I, THOMAS E. ARUNDEL, a citizen of the United States, residing at Omaha, in the county of Douglas and State 5 of Nebraska, have invented certain new and useful Improvements in Radio Reception Apparatus, of which the following is a specification.

The present invention relates to radio 10 reception apparatus and more particularly to devices which are known as detectors.

An object of this invention is to provide a detector which is of a permanent nature, but which is adapted to replace crystals and 15 the like heretofore used and at the same time to obtain the clearness and intensity of reception which is paramount to, or even greater than the most efficient crystal receivers at present known.

20 Another object of the invention is to provide a detector having a variable or adjustable contact surface comprising an infinitesimal number of contact or detector points so relatively positioned that but slight adjustment between the surfaces is necessary 25 to renew or change the relation between the contacts and thus is insured at all adjustments at least only or a few loud or clear points of contact.

30 A further object of the invention is to provide a detector having complementary surfaces adapted to be brought into proper contacting positions and which may have abrasions or roughened surfaces arranged 35 promiscuously on said surfaces so that variable and unpredicted contacts may be made during the relative movements of the surfaces to insure new combinations of contacts for effecting the desired results.

40 A still further object of the invention is to provide means for renewing or increasing these contact surfaces so that upon wear or grinding down of the surfaces the same may be renewed by the relative adjustment 45 of the same incident to the abrading action.

The invention still provides a substance of an abrasive or granular nature pocketed between the relatively movable surfaces of the detector adapted to cut and abrade the 50 surfaces irregularly so as to cause the irregular projections or depressions essential to the formation of the enumerable contact points desired.

With the foregoing and other objects in view, the invention will be more fully described hereinafter, and will be more particularly pointed out in the claims appended hereto.

In the drawings, wherein like symbols refer to like or corresponding parts throughout the several views.

Figure 1 is a sectional view through a detector constructed according to the present invention and mounted on the panel board, a fragment of the latter being shown.

Figure 2 is a detail sectional view through the detector removed from the panel board and socket.

Figure 3 is a side elevation of the same.

Figure 4 is an inner end elevation of the detector.

Figure 5 is an outer end elevation of the same, the thumb piece being removed.

Figure 6 is a detail face view of the fixed 75 element of the detector, showing on a greatly enlarged scale the particles or roughened surfaces of the element.

Figure 7 is a graphic illustration, greatly enlarged, of the abrasive particles which 80 may be used, showing the irregular contours of the same for cutting irregularly into the adjacent contact surfaces of the detector, and

Figure 8 is a detail face view of the movable 85 or adjustable element of the detector, showing the projections or serrations on its face.

Referring to the drawing, 10 designates a panel board or the like of usual construction and upon which is mounted a tubular socket 11 by means of bolts 12. The socket 11 is of a common well known type and provided with an outstanding annular flange 13 at its inner end and through which the bolts 12 are adapted to pass, the bolts carrying nuts in the ordinary manner for clamping the socket against the panel board 10 and about an opening 14 which is formed through the panel.

The flange 13 carries at preferably diametrically opposed points a pair of inwardly extending spring arms 14 and 15 which may be of flat spring metal and having their inner ends overturned upon themselves to form spring contacts 16 which are

normally urged forwardly in the socket 11 toward the panel board 10. The socket 11 is provided in one side and in its inner wall with a bayonet slot or groove 17 in the usual manner for facilitating the locking or retention of an electrical device in the socket.

Applicant takes advantage of this stock form of socket for the support and mounting of his detector and with such purpose in view has invented a detector which comprises a cylindrical block 18 adapted to freely fit within the socket 11 and which at its outer side is elongated to provide a supporting sleeve 19 through which is rotatably and slidably mounted a stem 20 carrying a thumb piece 21 on its outer end which is threaded or otherwise suitably secured to the stem 20 and by means of which the stem 20 may be rotated, oscillated or moved in and out through the sleeve 19. The cylindrical plug 18 is recessed at its inner side to provide a detector chamber 22 and in which is positioned a substantially semi-globular head 23 mounted on the inner end of the stem 20. Fitting in the detector chamber 22 and preferably toward the inner end of the block 18 is a fixed element 24 of the detector which may be of any suitable material and which is frictionally held in the cavity and in suitably spaced relation from the head 23 which constitutes the other detector element.

The inner face of the detector element 24 is concaved to at least partially conform to the spherical or globular configuration of the head 23 and to thus affect not only a relatively wide area of possible surface contact between the elements of the detector but to also provide a pocket or enclosure between the members for receiving and holding a quantity of abrasive particles 26 which may be carborundum or any other suitable substance comprising fine particles capable of abrading or cutting into the adjacent surfaces of the detector elements 23 and 24. These particles 26 will dig into the surfaces of the elements and cut and lift the same in uneven projections so that the surfaces, under the cutting action of the particles 26 will be formed in the rough contact bodies comprising enumerable projections which differ in length and size and which are irregularly positioned in the surfaces so that my manipulation of the head 23 different combinations of contacts may be formed and thus a continued and new adjustment of the detector may be had.

The abrasive particles 26 are enclosed in the chamber 22 and cannot escape from the plug 18 as the inner or fixed detector element 24 is frictionally held in place. In order to provide a contact between the fixed element 24 to hold the element firmly in position, a contact screw 27 is threaded into

the inner side of the block 18 in position to overlap the marginal portion of its head against the rear side of the element 24. This provides a contact 27 which is adapted to be brought opposite the spring contact 16 of the spring arm 15. The stem 20 is in electrical communication with a conductor strip 28 arranged in the sleeve 19 to bear against one side of the stem 20 and which is carried upwardly through the sleeve 19 and block 18 to a second contact screw 29 which has an enlarged head lying against the inner end of the plug 18. In this case, however, the contact screw 29 may be arranged so as to maintain its head out of line with the fixed electrode 24. The head of the contact screw 29 is mounted on the plug or block 18 in such position that when the latter is inserted in the socket 11 and properly positioned the head of the contact screw 29 will engage the spring contact 16 of the arm 14 and establish electrical communication between the arm 14 and the conductor strip 28. The plug or block 18 is provided at one side with a locking pin 30 which projects radially from the block and is adapted to enter the bayonet slot 17 for not only determining the proper positions of the contact screws 27 and 29 but to also hold the block or plug in the socket 11 against the tension of the spring arms 14 and 15. The spring arms 14 and 15 are connected to ground and antenna wires respectively with the suitable interposed instrumentalities or mechanism for receiving the transmitted vibrations.

The spring arms 14 and 15 may be secured in any suitable manner upon the socket flange 13 such as by screws 31 as shown and equipped with threaded sockets embedded in the rear side of the sockets. It is evident that the conductor strip 28 forms a connection with the stem 20 and head 23 so that the magnetic current may pass between the elements or electrodes 23 and 24 of the detector and the desired resistance provided by the imperfect contacts between raised or roughened surfaces of the elements and by the intercepting abrasive particles 26. From time to time the thumb piece 21 may be manipulated to disturb the relation between the electrodes 23 and 24 so as not only to grind one against the other with the intercepted particles 26 but also to reestablish the necessary electrical communication between the elements which is essential to maintain the detector in its efficient adjustment.

After the electrodes or elements have been properly adjusted such adjustment will be rigidly maintained on account of the adjustment being effected through the relatively large electrodes 23 and 24 because the stem 20 is frictionally held in the sleeve 19 by the spring action of the conductor strip 28. These large electrodes 23 and 24 will

thus maintain the smaller particles in proper contact and prevent their disturbance incident to vibration or jarring of the device.

Of course either one or both surfaces of the electrodes or elements 23 and 24 may be roughened so as to produce the projections from its surface, Figure 1 showing on a greatly enlarged scale the projections 32 carried upon the spherical surface of the head 23. Of course the electrodes 23 and 24 may be made of different kinds of material so that one may be hard and the other soft, or the electrodes may be given any other suitable configuration which is adaptable for the purpose and which will produce the desired effect of forming the projections 32 or the roughening of the surface of one or both of the electrodes.

The present invention as above described is an improvement on the construction disclosed in my co-pending application Serial No. 715,959, filed May 26, 1924, and which was allowed September 15, 1924.

I do not wish to be restricted to the size, form, and proportions of the various parts, and obviously changes could be made in the construction herein described without departing from the spirit of the invention, it

being only necessary that such changes fall within the scope of the appended claims. 26

What is claimed is:—

1. A detector for radio reception comprising a pair of relatively movable electrodes, and abrasive particles interposed between the electrodes for roughening the contact surfaces of the same. 35

2. In a detector, a block, a rotatable electrode mounted in the block, a second electrode mounted in the block interposed for electrical communication with the first electrode, and a surface roughening substance arranged for contact with the electrode by manipulation of one of the electrodes to roughen the surface of the same. 40

3. A detector for radio reception comprising a block, a fixed electrode mounted in the block, a movable electrode mounted in the block, said block being chambered about said electrode, and a quantity of abrasive particles enclosed in said chamber for engagement between and about the electrode for cutting the opposed faces of the same when the movable electrode is manipulated. 45 50

In testimony whereof, I have affixed my signature.

THOMAS E. ARUNDEL.
